UNITED STATES PATENT OFFICE.

MEREDITH CLARK, OF GARDEN CITY, NEW YORK.

MEASURING DEVICE.

1,034,424.

Specification of Letters Patent.

Patented Aug. 6, 1912.

Application filed February 29, 1912. Serial No. 680,633.

To all whom it may concern:

Be it known that I, MEREDITH CLARK, a citizen of the United States, and a resident of Garden City, in the county of Nassau and State of New York, have invented certain new and useful Improvements in Measuring Devices, of which the following is a specification.

This invention relates to an improvement in that class of devices which are intended to be applied to the necks of bottles in order that the person using the same may pour from the bottle a measured quantity, the device being particularly adapted for use in hospitals, sick rooms, kitchens and similar places.

I am aware that it has been proposed to attach to the necks of bottles a dose measurer whereby the contents of the bottle may be poured into the measuring device, and hence do not attempt to cover such broadly. But I believe that I am the first to construct a measuring device in such a way that the bottle may be tilted at one angle to pour the liquid from the bottle into the measure, or a spoon as I prefer to use it, and then tilt the bottle at another angle so as to discharge the contents of the measuring device or spoon, without necessarily corking the bottle.

The preferred embodiment of my invention consists of a clip to be secured to the neck of a bottle having a trough to deliver the liquid from the mouth of the bottle to a spoon which is pivotally supported near the end of the trough, the spoon being arranged at right angles to the trough, whereby when the bottle is tilted in one direction the liquid will pass from the mouth of the bottle through the trough into the spoon, and when the bottle is tilted at right angles, the contents will be discharged from the spoon.

Referring to the drawings: Figure 1 is a perspective view of a bottle having my invention applied thereto. Fig. 2 is a side elevation of a neck of a bottle with my device applied to it, the bottle being tilted in the act of pouring the liquid into the spoon. Fig. 3 is a side elevation of the part shown in Fig. 2, the bottle being tilted in the opposite direction so as to pour the contents from the spoon.

Referring now to the details of the drawings by numerals: 1 designates a spring clip which is formed in any desirable way but

preferably so that it will spring over the neck of an ordinary bottle. From the center of this clip projects a spout or trough 2 which is substantially in line with the upper surface of the mouth of the bottle, as illustrated best in Fig. 2. To the under side of the spout or trough 2 I form a bearing 3 into which is journaled a pin 4, this pin being connected by a curved shaped member 5 with a measuring device such, for example, as the spoon 6. The construction is such that when the device is held in the position shown in Fig. 1, the spoon will rest in a position so that the bowl of the spoon will be in the same plane with the mouth of the bottle, but when the bottle is tilted to the position shown in Fig. 2, the spout will move with respect to the spoon so that the spoon will still maintain a horizontal position but will be at an angle to the mouth of the bottle. The liquid in the bottle may be poured from the mouth of the bottle through the spout or trough 2 into the spoon, as illustrated in Fig. 2. After the desired quantity is poured into the spoon, the bottle may be tilted at right angles to the position shown in Fig. 2 so that the contents of the spoon may be placed to the mouth of the user and the liquid easily swallowed or the contents may be poured from the spoon into any desired receptacle.

My device is so simple that no further description of its use is necessary but I wish it understood that changes may be made without departing from the spirit of my invention. For example, the spoon may be of any desired size and if a large spoon is used, lines may be impressed in the spoon as indicated in Fig. 1 to measure larger or smaller quantities. For example, if the spoon shown in Fig. 1 is a dessert spoon, the dotted line 7 in said figure would indicate the amount necessary to fill a teaspoon.

What I claim as my invention is:

1. In a device of the character described, the combination of a measuring device, and means for securing it to the neck of a bottle, said device being pivoted to said means, the pivot running substantially in line with the length of the measuring device, whereby the bottle may be tilted at one angle to pour into the measuring device, and at another angle to empty the measuring device.

2. In a device of the character described, the combination of a spout, means for securing said spout to the neck of a bottle,

and a measure pivotally supported with relation to said spout, the length of the measure being at right angles to the length of the spout, whereby the bottle may be tilted at one angle to pour into the measuring device, and at another angle to empty the measuring device.

3. In a device of the character described, the combination of a spout, a spring clip for securing the same to the neck of a bottle, and a spoon pivotally supported with

respect to said spout, the pivot running substantially in line with the length of the spoon, whereby the bottle may be tilted at one angle to pour into the spoon, and at another angle to empty the spoon.

In testimony whereof I affix my signature in presence of two witnesses.

MEREDITH CLARK.
